UNITED STATES PATENT OFFICE.

DE FOREST HAWLEY, OF JOHNSON CITY, NEW YORK, ASSIGNOR TO UNION SPECIAL MACHINE COMPANY, OF CHICAGO, ILLINOIS, A CORPORATION OF ILLINOIS.

THREAD-CONTROLLING MECHANISM.

1,347,810.

Specification of Letters Patent. Patented July 27, 1920.

Application filed September 28, 1917. Serial No. 193,731.

To all whom it may concern:

Be it known that I, DE FOREST HAWLEY, a citizen of the United States, residing at Johnson City, in the county of Broome, State of New York, have invented certain new and useful Improvements in Thread-Controlling Mechanism, of which the following is a description, reference being had to the accompanying drawing and to the figures of reference marked thereon.

This invention relates to new and useful improvements in mechanisms for controlling the needle threads of two line sewing machines.

Heretofore, it has been customary, in two line sewing machines to control both needle threads by a single mechanism, and by reason of any inaccuracies in the loopers or in the timing of either looper to its respective needle, this single controller would fail to separately control the respective threads in a manner to form alike the stitches of both lines of stitching.

It is therefore the principal object of this invention to provide separate and relatively adjustable controlling means for the needle threads whereby either thread may be readily controlled to meet the demands of the corresponding looper, and thereby insure the formation of like stitches in both lines of stitching.

The invention therefore consists in the matters hereafter described and referred to in the appended claims.

In the accompanying drawings,—

Figure 1 is a front elevation of a two line sewing machine equipped with my improved needle thread controlling mechanism;

Fig. 2 is a partial end elevation thereof, parts being shown in section;

Fig. 3 is an enlarged detail view, the needle bar being at the lower end of its stroke; and

Fig. 4 is a detail perspective view of the thread controlling lever.

My invention is especially adapted for use in a two line machine including two needles and two loopers. A needle lever reciprocates the needle bar and the loopers. The needle threads are led through suitable tensions, through spaced thread guides carried by the needle lever, and thence through thread guides on the needle bar to the respective needles. A thread controlling lever

is pivoted on the overhanging arm of the machine, and this lever is oscillated at each rise and fall of the presser foot. The end of this controlling lever carries two thread eyelets which are mounted for relative vertical adjustment and are disposed intermediate the two thread guides carried by said needle lever. The relation of these eyelets relative to the thread guides on the needle lever is what determines the distances the thread loops are run upwardly along the needles during the last part of the downward movement thereof, and consequently this determines the amount of thread employed in the formation of each stitch of both lines of stitching. Should one looper cast its needle thread loops before the other casts its loop, or, if the cross-sectional thickness of one looper is greater than that of the other looper, then, with only a single controlling means for both threads, the stitches of one line will be looser than the stitches of the other line. By employing separate controllers which are capable of relative adjustments, said objectionable features can be readily eliminated.

Referring to construction shown in the drawings, the sewing machine includes a bed 1 carrying an overhanging arm 2 in which reciprocates a needle bar 3. The needle bar 3 is reciprocated by a needle lever 4 which is pivoted to said overhanging arm 2 and actuated by a pitman coöperating with an eccentric on the main shaft 6. The needle bar carries two needles 7 and 8, and coöperating with these needles are two thread carrying loopers 9 and 10 for forming two lines of double locked stitches. In this instance, both loopers are mounted on a single looper rocker 11 and this rocker is oscillated by a rod 12 from the needle lever extension 13. Coöperating with the stitch forming mechanism is a four motion feed dog 14 of usual construction and operated in the ordinary manner in slots formed in the work support. A presser foot 16 coöperates with the feed dog and work support, and this foot is carried by a presser bar 17 mounted in suitable bearings in the overhanging arm and normally pressed downwardly by a spring 18 see Fig. 2.

Needle threads 19—20 are led from the supply through tensions 21—22 fixed on the overhanging arm, thence through spaced

thread guides 23—24 fixed on the needle lever, and thence through a suitable guide 25 to the respective needles 7—8.

Pivottally mounted on a stud 26 fixed to 5 the overhanging arm 2, is a main thread controlling lever 27 which is formed at one end with a segment 28 meshing with a rack 29 adjustably fixed to the presser bar. The other end of the controlling lever is disposed 10 between the thread guides 23—24, and carries a thread eyelet 30 through which the thread 19 is led. Pivottally mounted upon the main controlling lever 27 is an auxiliary controlling lever 31, the pivot screw being 15 indicated at 32. One end of this auxiliary lever carries a fixed thread eyelet 33 which is disposed in substantially the vertical plane extending between the guides 23—24 and including the eyelet 30. The other end 20 of this auxiliary lever is formed with a slot 34, and a screw 35 passes through said slot and is threaded into the main controlling lever 27. The slot and screw connection permits the auxiliary lever to be adjusted about 25 its pivot so as to vary the vertical position of the eyelet 33 through which the thread 20 is led.

In operation, while the needles are reaching the lowermost position, the loopers are 30 retracting and shed their needle-thread loops which were therearound. The loops are shed just as the points of the loopers pass their respective needles, and before the needles reach their lowermost position. Controlling means must therefore be provided to run said needle-thread loops upwardly along the needles to a point of sufficient height to prevent the loopers from entering said loops for the second time. By reason 40 of the thread guides 23—24 moving downwardly away from the eyelets 30—33, both thread loops are caused to elevate above the plane of travel of the loopers. If the points of both loopers do not permit of their 45 respective loops being cast off simultaneously, then one loop will not be pulled upwardly as high as the other, and consequently the larger loop will create looser stitches than the other. Furthermore, one needle thread 50 loop may be larger than the other on account of the cross sectional thickness of one looper being greater than the other. It is therefore important that both needle thread loops when pulled up, should be of the same 55 size. Should either of the above conditions occur, it is only necessary to regulate the vertical positions of either or both controlling eyelets 30 and 33, and thereby separately and uniformly control both needle 60 thread loops.

By means of the rack 29 and lever 27, both controlling levers will be automatically and simultaneously adjusted when fabrics of different thicknesses are being sewed.

65 Having thus described my invention, what

I claim as new and desire to secure by Letters Patent, is:—

1. The combination with a plurality of needles, a looper coöperating with each needle, tension means through which the threads are led from the supply to the needles, and separate means acting on the respective threads between the tension means and the needles for controlling the amount of thread used in the formation of each stitch, said separate means including devices whereby the same may be adjustable to independently vary the degree of control on the respective threads. 70

2. In a sewing machine the combination with an overhanging arm, a needle bar carried thereby, needles mounted on said bar, a needle lever for reciprocating said needle bar, loopers respectively coöperating with said needles, spaced thread guides carried by said needle lever, and thread eyelets for controlling the respective threads supported on the overhanging arm for relative vertical adjustment and disposed intermediate said thread guides. 80

3. In a sewing machine the combination with an overhanging arm, a needle bar carried thereby, a needle lever for reciprocating said needle bar, loopers respectively coöperating with said needles, spaced thread guides carried by said needle lever, a main lever fixed to the overhanging arm and carrying a thread eyelet, and an auxiliary lever carried by said main lever and carrying a thread eyelet, said thread eyelets being disposed intermediate said thread guides, one of said levers being adjustable relative to the other to vary the controlling action of its thread eyelet. 90

4. A sewing machine including in combination an overhanging arm, a presser foot, a presser bar carrying said presser foot and mounted in the overhanging arm, a needle bar reciprocating in said overhanging arm, a pair of needles carried thereby, a needle lever for reciprocating said needle bar, a looper coöperating with each needle, means mounted on the overhanging arm carrying thread guiding devices, one for each needle thread, thread guiding devices carried by the needle lever and engaging the needle threads at opposite sides of the first-mentioned guiding devices, devices for connecting said means mounted on the overhanging arm with the presser bar whereby vertical movements of the presser bar shift the guiding devices carried thereby, and means whereby one of said guiding devices may be adjusted relative to the other and to their connection with the presser bar. 100

5. A sewing machine including in combination an overhanging arm, a presser foot, a presser bar supporting said presser foot, a plurality of needles, a looper coöperating with each needle, tension devices through 110

which the threads are led to the needles, a needle bar carrying said needles, a needle lever operating said bar, spaced thread guides carried by said needle lever, a main 5 thread controlling lever pivoted to the overhanging arm and carrying a thread eyelet for engaging one of the needle threads between the guides on the needle lever, an auxiliary lever adjustably carried by the main 10 lever and carrying a thread eyelet engaging the other needle thread between the thread

guides on the needle lever, and means connecting the presser bar with the main lever whereby said main lever is shifted through the vertical movements of the presser bar. 15

In testimony whereof, I affix my signature, in the presence of two witnesses.

DE FOREST HAWLEY.
